(57) **CLAIM**

I claim the ornamental design for a hunting knife, as shown and described.

DESCRIPTION

FIG. 1 is a perspective view of the hunting knife design;
FIG. 2 is a side view of the hunting knife design;
FIG. 3 is a side view of the hunting knife design;
FIG. 4 is a top view of the hunting knife design;
FIG. 5 is a bottom view of the hunting knife design;
FIG. 6 is a front view of the hunting knife design; and,
FIG. 7 is a rear view of the hunting knife design.

Any broken lines in the figures depict environment and are included for the purpose of illustrating only and form no part of the claimed design.
